UNITED STATES PATENT OFFICE

SILVESTRE F. WILSON, OF OAKLAND, CALIFORNIA

DESIGN FOR A GARMENT HANGER

Application filed May 1, 1931. Serial No. 39,670. Term of patent 14 years.

To all whom it may concern:

Be it known that I, SILVESTRE F. WILSON, a citizen of the United States, and a resident of Oakland, in the county of Alameda and State of California, have invented a new, original, and ornamental Design for Garment Hanger, of which the following is a specification, reference being had to the accompanying drawings, forming part thereof.

I claim:
The ornamental design for a garment hanger substantially as shown.

SILVESTRE F. WILSON.
